R. H. & E. A. EVERETT.
COOKING UTENSIL.

No. 322,532.

Patented July 21, 1885.

Fig. 1.

Fig. 2.

UNITED STATES PATENT OFFICE.

RICHARD H. EVERETT AND ELIZA A. EVERETT, OF VESTAL CENTRE, NEW YORK.

COOKING-UTENSIL.

SPECIFICATION forming part of Letters Patent No. 322,532, dated July 21, 1885.

Application filed September 22, 1884. (No model.)

To all whom it may concern:

Be it known that we, RICHARD H. EVERETT and ELIZA A. EVERETT, citizens of the United States, residing at Vestal Centre, in the county 5 of Broome and State of New York, have invented a new and useful Improvement in Cooking-Utensils, of which the following is a specification, reference being had to the accompanying drawings.

10 Our invention relates to cooking-utensils; and it has for its object to provide a device of this character adapted for use as a steamer, and with means whereby steam may be carried to the oven when bread, meats, or other articles 15 are being baked, in order that the said articles may be kept moist in a slight degree, and thus prevent them from becoming hardened.

15 A further object of the invention is to provide a cooking-utensil for the purposes described which shall be cheap and simple in its construction and efficient and effective in its operation.

With these ends in view the invention consists in the improved construction of steamer, 20 in the means for conveying steam to the oven, and in the details of construction and combinations of the various parts hereinafter fully described, and pointed out in the claims.

25 In the drawings, Figure 1 is a perspective view of a cooking-utensil constructed in accordance with my invention, showing the same applied to a stove. Fig. 2 is a vertical section of the steamer.

30 In the accompanying drawings, in which like letters of reference indicate corresponding parts in all the figures, A represents the stove, which is of any ordinary or well-known construction.

35 B represents the oven of the stove, and C 40 designates a boiler. Near the lower end of this boiler is provided an escape-cock or faucet D, while said boiler is provided with an opening near its upper end.

45 E represents a jointed pipe, which is fitted in the hole or opening in the boiler at one end, its other end extending downwardly and entering a hole in the wall of the oven. It will thus be seen that as steam is generated it will pass from the boiler through the pipe E into 50 the oven and thus moisten the air. We have provided a cut-off, G, near the upper end of

the pipe E, so that when the oven is not in use the steam may be shut off from that point. This cock G may be of any ordinary or well-known construction.

55 H represents the steamer, which fits in the top of the boiler C, and is supported by an annular flange, a, which rests on the top of the said boiler. The bottom of the steamer has raised portions b, having each an opening in 60 their top, said raised portions being of substantially a truncated cone shape. It will be seen that by having these raised portions that the water of condensation cannot pass back into the boiler, as it will collect between the 65 raised portions b. By this arrangement a number of advantages are obtained; but more particularly preventing the water in the boiler from becoming impregnated with odor from the articles being cooked in the steamer. Thus 70 it will be seen that the steam that is admitted to the oven is perfectly pure and does not impart any taste or odor to the articles therein contained.

75 The steamer is provided with a cover, H, and with a handle, I, to permit of its being moved from place to place.

When the steamer is not in use, the cover of the same may be removed therefrom and used upon the boiler.

80 The devices above described are simple in their construction, may be supplied at a slight cost, and are thoroughly efficient.

Having fully described our invention, what we claim as new, and desire to secure by Letters Patent, is—

85 The apparatus described, comprising the boiler, the steamer having an annular flange, a, the raised portions b, having holes or openings in their upper ends, and a pipe leading from said boiler, whereby it may be applied to the oven of a stove and connect therewith, substantially as set forth.

In testimony that we claim the foregoing as our own we have hereto affixed our signatures 90 in presence of two witnesses.

RICHARD H. EVERETT.
ELIZA A. EVERETT.
